UNITED STATES PATENT OFFICE.

LOUIS WOJIDKOW, OF BROOKLYN, NEW YORK.

DESIGN FOR A KETTLE.

SPECIFICATION forming part of Design No. 25,480, dated May 12, 1896.

Application filed April 11, 1896. Serial No. 587,225. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for Kettles, of which the following is a specification, reference being had to the accompanying drawing, which shows a perspective view of the same.

10 The leading feature of my design consists of a body having the peculiar outline as shown, the upper edge of which is flared outwardly and scalloped, and from which body extend two curved decorated arms, the ends 15 of which are joined by a straight handle.

A represents the body of the kettle, having the peculiar outline as shown, and from which

extends the spout B, the upper edge of said body having the outwardly-flared and scalloped edge C. From the said body extend 20 the two curved decorated arms D, which, together with the connecting-piece E, form a handle for said kettle.

F represents the top or lid, fitting within said upper overhanging edge of the kettle-body.

What I claim is—

The design for a kettle substantially as herein shown and described.

LOUIS WOJIDKOW.
